UNITED STATES PATENT OFFICE.

JOSEF BRANDSTETTER, OF ROCHESTER, MINNESOTA, ASSIGNOR TO CONLEY CAMERA COMPANY, OF ROCHESTER, MINNESOTA, A CORPORATION OF MINNESOTA.

SHUTTER FOR CAMERAS.

1,275,836.

Specification of Letters Patent. Patented Aug. 13, 1918.

Application filed November 20, 1917. Serial No. 202,899.

To all whom it may concern:

Be it known that I, JOSEF BRANDSTETTER, a citizen of the United States, residing at Rochester, in the county of Olmsted and State of Minnesota, have invented certain new and useful Improvements in Shutters for Cameras, of which the following is a specification, reference being had therein to the accompanying drawing.

10 My invention relates to photographic cameras and has for its object the production of improved shutter operating means.

My present invention relates to the type of shutter described and claimed in Letters 15 Patent Nos. 732,175, granted June 30, 1903, and 739,834, granted September 29, 1903, to F. V. and K. E. Conley. In said patented type, a pair of shutter leaves are carried on rotating shafts and fold together so as to 20 overlap when the shafts are turned in one direction, while they open wide to expose the lens orifice when the shafts are turned in the opposite direction. To accomplish this turning, the shafts have terminal cranks, 25 those on one end being connected so that the shafts will turn simultaneously but in opposite directions, while a single shaft on the other end is connected with an operating bulb and also with a retracting spring, to 30 turn the shutters into closed position. Other features in the patents need not be adverted to herein as the present invention has to do principally with the shaft operating mechanism, and an improved plunger or piston 35 arrangement for operating the same.

It will be observed that in the former patents the retracting spring in each case is attached to the operating crank, and that the whole strain of maintaining the shutter open 40 is sustained by the bulb mechanism, so that in case of a slow leak or other defect therein, it would be difficult to maintain the shutters open with certainty and precision, and at the same time have a spring action sufficient 45 to insure prompt and reliable closing. The patented apparatus, nevertheless, has proved very efficient in practice, and the present invention perfects the same by removing the possibility noted, and rendering the action 50 of the bulb mechanism, and the shutters noiseless, certain, and precise under all conditions.

Very briefly stated, the improvement consists in the provision of an operating plunger 55 connected to a crank on one shaft, and a long

helical retracting spring connected to a crank on the other shaft, the two shafts being connected by means of a connecting rod on the opposite side of the shutter from the plunger. The retracting spring crank is so 60 set that the spring will move past center in each direction when the shutter is closed or opened, thus taking all strain off the operating bulb or plunger and preventing any premature operation of the shutter in case 65 of an accidental leak as well as rendering unnecessary an absolutely air-tight fit of the plunger or piston.

My invention is illustrated in the accompanying drawings in which—

70 Figure 1 is a top plan view of my improved shutter, and

Fig. 2 is a rear elevation of the same.

In the drawings, 1 indicates inside front wall of a camera casing having an exposure 75 opening 2, to be uncovered and covered by the shutter in operation. The shutter proper consists of two leaves 3 and 4, secured respectively to the shafts 5 and 6, passing through and journaled in top and bottom plates 7 and 8, which serve also as light guards to prevent leakage of light past the edges of the shutters when they are closed. When fully opened, the leaves 3 and 4 are received within cushioning wings 9 and 10 80 respectively, having extensions supplementing the plates 7 and 8, so as to form a complete box around the opening 2. The wall 1 of the camera is usually made of wood and inside the box formed of the plates 7—8 and 85 the wing extension, an extra thickness of wood is provided covered on its face with felt designated by the numeral 11. When closed, the leaves rest against this felt surface.

90 The two shafts 5 and 6 are provided respectively with cranks 12 and 13, linked together by a connecting rod 14, the cranks being oppositely set, that is to say, one being down while the other is up and the link diagonal, so that the cranks will turn the shafts in opposite directions when moving together. The shaft 6 has an operating crank 15 connected by means of a straight connecting rod 16 to the plunger or piston 100 17 of a pneumatic cylinder 18, supplied with air through a nipple 19, and a rubber tube 20 terminating in a bulb 21 having an opening 22 indicated in dotted lines in Fig. 2. The shaft 5 has a spring crank 23 set oppositely 105 24 to the crank 12, so that the plunger will be moved past center in each direction when the shutter is closed or opened. The connecting rod 14 is so 110 set that the cranks 12 and 13 will move in opposite directions when the shutter is closed or opened.

to the crank 15 and having secured to it at one end a long helical spring 24 the other end of which is secured to an anchor 25, near the crank 15. The length of this spring 5 and the distance of its anchorage point 25 renders it possible to set the crank 23 so that a straight line connecting it with the point 25 in its two extreme positions would fall on opposite sides of the crank shaft axis 5; 10 or in other words so that the spring 24 will snap past center as the shaft 5 oscillates and the shutters 3 and 4 open and close. This is clearly illustrated in Fig. 1 which shows the shutters open and the spring past center on 15 one side of the crank 23.

The pneumatic cylinder 18 is constructed in the form of an open ended dashpot with the nipple 19 on the closed end. The piston 17 is formed as shown in cup shape with extended side walls smoothly fitted to the internal walls of the cylinder, which may be by grinding or otherwise.

In operation, the thumb of the operator is placed over the opening 22 in the bulb 20 25 and the bulb compressed, whereupon air will be forced in the cylinder 18 behind the piston, forcing the latter to the right in the drawing, thereby turning the crank 15 and through the connected cranks 13 and 12 and 30 the connecting rod 14, turning the shaft 5 in the reverse direction, opening the shutters to the extreme position shown in the drawings. The spring 24 having passed center tends to maintain the shutter leaves in open 35 position, by keeping a strain on the crank 23, hence the thumb may be removed from the bulb and the operator may have the free use of both hands while the shutter is open. In order to close the shutter, the bulb 20 is 40 again compressed, the thumb or finger then placed upon the orifice 22, and the bulb allowed to expand. This withdraws the air from the cylinder 18, pulls in the piston 17, turns the cranks 15, 13, 12 and 23, until the 45 spring 24 is again past center, when the spring tension will be added to the suction effect on the piston to accelerate the return motion of the leaves 3 and 4.

The cranks are so set that when the leaves 50 are completely closed, the spring 24 is again past center, and its tension maintains the shutter securely and safely closed until the bulb is again compressed.

Having thus described my invention what 55 I claim and desire to secure by Letters Patent is—

1. In a mechanism of the character described, the combination with a frame having an opening therein, and a shutter normally closing said opening, of an air cylinder secured to the frame, a piston in said cylinder, a rod secured to the piston and projecting from one end of the cylinder, mechanism between said rod and said shut-

ter, whereby when said rod is moved in one 65 direction, the shutter will be opened, and a spring normally closing said shutter, said spring being connected to an oscillating part of the shutter and having its anchorage adjusted with respect thereto so that when the 70 shutter is open the spring will be past the center of oscillation in one direction, and when the shutter is closed the spring will be past the center of oscillation in the other direction. 75

2. The combination with a lens board carrying shutter leaves, of pneumatic cushioning means disconnected from but operating to prevent noise and absorb jars and vibrations incident to the operation of the leaves, 80 and a spring connected at one end to the lens board and at the other end to an oscillating portion of the leaves, the point of securing to the lens board being so adjusted with respect to the oscillating point that the 85 spring will go past center in opposite directions when the shutter is closed and when it is open.

3. The combination with a lens board carrying shutter leaves and means for opening 90 and closing the same, of pneumatic cushioning devices disconnected from but operating to prevent noise and absorb jars and vibrations incident to the operation of the leaves, and a spring connected at one end to the lens 95 board and at the other end to an oscillating portion of the leaves, the point of securing to the lens board being so adjusted with respect to the oscillating point that the spring will go past center in opposite directions 100 when the shutter is closed and when it is open.

4. The combination with a lens board and shutter leaves carried thereby, of pneumatic cushioning means disposed at an angle to 105 the lens board and disconnected from the leaves, means connecting the leaves for opposite but simultaneous movement, a crank on one leaf, and a spring connecting said crank to the lens board at a point so adjusted that the spring will move past the center of oscillation of the crank in opposite directions when the shutter is open and when it is closed. 110

5. The combination with a lens board and shutter leaves carried thereby, of pneumatic cushioning means disposed to one side of and at an angle to the lens board and disconnected from the leaves, means connecting the leaves for opposite but simultaneous 115 movement, a crank on one leaf, and a spring connecting said crank to the lens board at a point so adjusted that the spring will move past the center of oscillation of the crank in opposite directions when the shutter is open and when it is closed. 120

6. In a mechanism of the character described, the combination with a frame or

lens board having an opening therein, and a shutter normally closing said opening, of a pneumatic controlling device secured to the frame, means for operating said pneumatic device, a connection from said device to the shutter, pneumatic cushioning means disconnected from but operating to prevent noise and absorb jars and vibrations incident to the operation of the shutter, and mechanical operating means for the shutter 10 so operating as to move past center in each direction when the shutter is opened and closed by the pneumatic controlling device.

In testimony whereof I affix my signature.

JOSEF BRANDSTETTER.
